US0D1029238S

(12) **United States Design Patent** (10) **Patent No.:** **US D1,029,238 S**
(45) **Date of Patent:** **** May 28, 2024**

(54) **INHALER**

(71) Applicant: **BESPAK EUROPE LIMITED**, King's Lynn (GB)

(72) Inventor: **Ian Mahaffy**, King's Lynn (GB)

(73) Assignee: **BESPAK EUROPE LIMITED**, King's Lynn (GB)

(**) Term: **15 Years**

(21) Appl. No.: **29/858,041**

(22) Filed: **Oct. 27, 2022**

(30) **Foreign Application Priority Data**

Apr. 27, 2022 (GB) 6204934

(51) **LOC (14) Cl.** **24-02**

(52) **U.S. Cl.**

USPC **D24/110**

(58) **Field of Classification Search**
